WITNESS:

BY Victor J. Evans
ATTORNEY

UNITED STATES PATENT OFFICE.

GEORGE R. SCHROEDER, OF BEVERLY, KANSAS.

PIN HOLDER.

Application filed September 29, 1922. Serial No. 591,417.

To all whom it may concern:

Be it known that I, GEORGE R. SCHROEDER, a citizen of the United States, residing at Beverly, in the county of Lincoln and State 5 of Kansas, have invented new and useful Improvements in Pin Holders, of which the following is a specification.

This invention relates to improvements in pin holders and has for its principal object 10 to produce a device of this character which will clamp a paper of pins therebetween.

Another object of the invention is the provision of a pin holder formed of a pair of angular plates which have openings formed 15 centrally thereof to receive clamping means for clamping a paper of pins or the like between said plates.

A further object of the invention is the provision of a pin holder formed of metal 20 plates and the base of these plates are bent outwardly and curved upwardly at their edges to provide trays which are designed to receive loose pins therein.

This invention also consists in certain 25 other features of construction, and in the combination and arrangement of the several parts, to be hereinafter fully described, illustrated in the accompanying drawing, and specifically pointed out in the appended 30 claims.

In describing my invention in detail, reference will be had to the accompanying drawing, wherein like characters of reference denote like or corresponding parts 35 in the several views, and in which:—

Figure 1 is an end view of the invention in clamping engagement.

Figure 2 is a top plan view of the same.

Figure 3 is a vertical sectional view taken 40 on line 3—3 of Figure 1.

Figure 4 is a detail view of the clamping member forming a part of the invention.

Referring now to the drawing, wherein like characters of reference denote corresponding parts, 1 indicates a pair of plates rounded outwardly at the bottom thereof, and bent to provide trays 2, which have their edges upturned, as at 3, to receive loose pins, paper clips, or the like. The plates

have elongated openings 4 formed therein 50 to receive a U-shaped spring clamping member 5 for clamping a paper of pins or the like therein, and these pins may project above the top of the plates so as to be easily removed from the paper.

From the above, it will be seen that after a paper of pins has been placed between the plates, the U-shaped spring member will permit the upper edges thereof to be opened without removing the U-member, by simply exerting a pressure upon the outwardly bent flanges or trays. It will be apparent that two plates are formed in such a manner that they hinge one on the other, and therefore make it unnecessary to take the same apart 60 in inserting a paper of pins or removing the same.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A pin holder comprising a pair of angular metallic plates rounded outwardly at the bottom thereof to provide trays which have their edges upturned, said plates having openings formed centrally at the bottom thereof, and a U-shaped clamping member, engaging said openings for clamping a paper of pins between said plates.

2. A pin holder comprising a pair of plates having vertically disposed portions adapted to be arranged in spaced relation and being angularly bent to form oppositely disposed trays, said plates being provided with aligned elongated openings intermediate 80 their ends at the juncture of the vertical portion with the tray, and a substantially U-shaped spring clamp passing through the aligned openings and engaging the vertical portions for the purpose specified.

In testimony whereof I affix my signature.

GEORGE R. SCHROEDER.
